UNITED STATES PATENT OFFICE.

HARRY A. ATWATER, OF KANSAS CITY, MISSOURI.

FURNACE CONSTRUCTION.

Application filed January 16, 1922. Serial No. 529,696.

To all whom it may concern:

Be it known that I, HARRY A. ATWATER, a citizen of the United States, and resident of Kansas City, Jackson County, State of Missouri, have invented a certain new and useful Improvement in Furnace Construction, of which the following is a complete specification.

The present invention relates to furnaces, and aims to provide a novel construction having various features of improvement as regards the feeding of the air required for supporting the combustion and the preheating of such air, and also the construction and arrangement of the floor of the combustion chamber to produce a more effective combustion and transmission of heat to the incoming air, as well as an efficient drainage of any excess fuel where a liquid fuel is being used.

To this end, I have devised a furnace structure in which an air-feed passage is provided and the flow of the incoming air so conducted as to subject it to the preheating action of increasingly hotter portions of the floor of the combustion chamber throughout the course of such air through said passage to the point of discharge into the combustion chamber. In its course through the passage I further provide means for subdividing the flow of air at intervals in such a manner that a more uniform travel of the air is effected than is the case where a single unmodified current of air is moving through an air-feed conduit.

I have also devised an improved floor construction for the combustion chamber of the furnace whereby a more effective combustion is maintained by virtue of the floor being pitched at a certain angle for the purpose of utilizing the reflective properties of the floor for throwing back the heat in the direction of the fuel-feed compartment and thus heating this compartment at a most efficient temperature. This pitch or slope of the furnace also facilitates the proper drainage of the same in case a liquid fuel is being supplied to the furnace, and for such fuel the floor is made liquid-tight to prevent the fuel from leaking through and burning or damaging other parts of the furnace structure. I have further devised a floor construction of not only a simple and comparatively inexpensive type, but one which will promote the transmission of heat therethrough to the air

beneath and thereby maintain an efficient preheating action.

With these general objects in view, the invention will now be described by reference to the accompanying drawings illustrating one form of construction which I have devised for embodying the proposed improvements, after which the novel features therein will be particularly set forth and claimed.

In the drawings—

Figure 1 is a longitudinal sectional view, illustrating a furnace structure embodying the present improvements, and representing a section taken on the line I—I of Figure 2;

Figure 2 is a horizontal sectional view, representing a section taken on the line II—II of Figure 3;

Figure 3 is a vertical sectional view, representing a section taken on the line III—III of Figure 2; and

Figures 4 and 5 are sectional detail views, taken on the lines IV—IV and V—V, respectively, of Figure 2.

Referring to the drawings in detail, these show a furnace structure comprising side walls 10 and end walls 11 of any preferred form for providing a furnace combustion chamber 12. The floor of this combustion chamber I construct of tiling 14 extending continuously in a gradual downward slope from what may be termed the rear wall 11 toward the opposite wall of the chamber 12, this tiling being supported upon a sheet metal supporting structure preferably formed of metal plates 15 having marginal interengaging tongue and groove flanges 16, 17, respectively (see Figure 4), a set of supporting angles 18 being arranged for carrying the outer edges of the plates 15 around the walls 11, 12, and also at intervals transversely across intermediate portions of the floor, as shown in Figure 1. This type of construction provides a floor which readily transmits heat from the combustion chamber to the space beneath the floor which is utilized for preheating the air supplied to the combustion chamber as hereinafter explained, and also affords a liquid-tight flooring which prevents said liquid fuel from leaking through, and the slope of the floor facilitates proper drainage of any excess or unburned fuel from the combustion chamber.

For this drainage, a channel or conduit 20 is made from suitably formed

sheet metal 21 secured to those edges of the plates 15 which surround the air-feed opening 22 through the floor beneath the fuel feed or burner compartment 23 formed by an arch 24 supported at an angle similar to the inclination of the floor of the combustion chamber 12. The channel 20 extends transversely along the rear margin of the opening 22, and thence inclines forwardly along one side of said opening, cross strips 25 being used to stiffen and brace the metal forming the channel (see Figure 5). An outlet pipe 26 drains the channel or conduit 20 to the exterior of the furnace.

15 The air space beneath the floor of the combustion chamber is partitioned to provide air-feed passages similarly arranged at opposite sides of the middle longitudinal line of the furnace, for conducting and also pre-
20 heating the air required to be supplied to the combustion chamber in the operation of the furnace. This partition structure comprises a pair of vertical partitions 30 extending longitudinally from the front wall 11 and terminating some distance short of the rear wall, where both partitions 30 are joined to a transverse partition 31 between the side walls 10 of the furnace. Thus an inlet air passage 32 is formed between each 25 of the side walls 10 and one of the partitions 30, an air intake opening 33 being provided in the front wall 11 for each of said passages 32. Across each passage 32 is arranged a vertical partition 34 provided with 30 a plurality of openings 35, and the partition 31 is similarly provided with a plurality of openings 35, the function of which is to subdivide the incoming air into a plurality of streams and thereby cause the whole 35 current of air to travel at a more even or uniform rate. Both passages 32 communicate with a transverse passage 36 at the rear of the partition 31, and from there the air is again passed through openings 35 in the 40 middle portion of the partition 31 into a central passage 37 between the longitudinal partitions 30, and which conducts the air to the opening 22 communicating with the burner compartment 23. By this means the 45 incoming air is caused to pursue a course, as indicated by the arrows in Figure 2, in which the air is subjected to the preheating effect of successively and increasingly hotter portions of the bottom face of a combustion chamber floor. This gradual increase in the heating action on the air takes place throughout the course of the air to the burner compartment, since it is apparent that the side margins of the combustion chamber 50 floor are relatively cooler, and the rear portion of said floor (in the illustrated arrangement) is at a higher temperature, while the temperature of the middle portion is still higher and increases to a maximum in the 55 vicinity of the burner compartment 23.

For the purpose of illustration, I show a type of oil burner 40 within the fuel-feed compartment 23, although it will be understood that the furnace structure is equally well adapted for use with any form of liquid, 70 gaseous or finely-divided form of fuel, and also for burners in either single or multiple form, with the air-feed passages adapted to suit any required arrangement of the burners.

75

It is thus apparent that I have devised an efficient and practical construction for carrying out the desired objects of the invention. A distinct advance is made over prior constructions using openings at various 80 points in the combustion chamber floor for obtaining the required air circulation, which allows the liquid fuel gathering on the floor to drip through and then burn fiercely below the floor, doing serious damage by burning out surrounding parts of the furnace structure. The liquid-tight flooring herein described overcomes this defect while fulfilling all the requirements as regards the circulation of the air. The structure of the 85 flooring itself is also a decided improvement, in that it comprises practically a single layer of refractory material which promotes the transmission of heat to the surface beneath as required for the efficient preheating of 90 the air supply, and the slope of the floor, in addition to its liquid-tight character, facilitates the proper drainage of any oil collecting thereon and the removal of the same by way of the channel 20 which dis- 95 charges into the outlet pipe 26.

100

Another equally important function which characterizes the slope or pitch of the floor of the combustion chamber is its capacity for reflecting the heat away from the rear 105 end of the combustion chamber toward the burner compartment for maintaining the latter at an efficient high temperature, and the arch 24 is correspondingly pitched in order to accentuate this effect. It is well understood that the zone around the burner, for obtaining the most effective combustion, must be maintained at the highest temperature practicable, because of the great absorption of heat incurred in the vaporization of 110 the fuel, and the above described construction, including that for regulating the flow of the air supply, is carefully designed to not only reflect toward the burner compartment but also guard against any loss of 115 heat from the burner zone for air-preheating purposes. Accordingly, the flow of the air is so controlled as to gradually heat it first from the relatively cooler portions of the combustion chamber floor, and thereafter 120 bring up its temperature by conducting it across surfaces that are increasingly hotter as the air approaches the point of discharge into the burner compartment. This is the 125 most efficient method of preheating which 130

could be adopted for the purpose, since it obviously follows substantially what is known as the counter-current principle of heat exchange or absorption.

5 In this connection an improvement of considerable advantage is made by subdividing the flow of air in the air passages or conduits by means of the openings 35 in the transverse partitions, which has the effect 10 of intermittently separating the main air current into a plurality of separate smaller streams and tending to produce a more uniform average rate of movement of the whole air flow; without such a subdivision of the 15 air flow, the movement would obviously be greatly retarded, by friction, along the walls of the passage, and the flow of the central portion of the current would be relatively much faster, thus resulting in unsymmetrical 20 conditions as regards both the general movement of the air and also the preheating effect thereon, which would be of a non-uniform character. Attempts have been made to correct this disadvantage by providing 25 separate conduits, with the result of only increasing the trouble, due to the greatly increased friction introduced, and the obstructing of the air flow as well as the transmission of the heat from the combustion 30 chamber floor. In the present case, it is found that this control of the movement of the air, combined with the efficient pre-heating thereof, and also with the above described forward pitch of the floor of the 35 combustion chamber, provide such burner zone temperature conditions as to facilitate the steady burning of the fuel and maintain such steady burner action at even lower than the average rates (that is, with low 40 burner flame) and without danger of the flame being extinguished. The improved construction is adapted for any type of furnace duty, and it is found that by modifying existing installations to embody one or 45 more of the features of the improvements the effective capacity of the installation may be very materially increased by virtue of the more rapid and more nearly perfect combustion which is made possible by means 50 of the improvements and which is attended by a much lower percentage of excess air than is the case with the older designs of construction.

55 While I have herein described and illustrated what I now regard as the preferred form of construction for embodying the aforesaid improvements, it is obvious that the same is susceptible of many changes and variations in form without departing from 60 the primary principles of the invention, and I therefore desire to reserve the right to make all such changes or modifications as may fairly fall within the scope of the appended claims.

65 What I claim is:

1. A furnace construction comprising a combustion chamber having a floor and an air feed passage beneath said chamber for conducting air from the exterior of the furnace into said combustion chamber, and a 70 partition structure in said passage arranged to direct the air in a course traversing increasingly hotter portions of the under face of the floor of said combustion chamber throughout said passage to its place of discharge into said chamber. 75

2. A furnace construction comprising a combustion chamber having a floor and an arch forming a fuel-feed compartment at one end of said chamber, the floor of said chamber having a gradual downward slope from the other end of said chamber in the direction of said fuel-feed compartment, and said arch also sloping at an inclination 80 similar to the slope of said floor. 85

3. A furnace construction comprising a combustion chamber having a floor and a fuel-feed compartment at one end thereof, and an air feed passage beneath said chamber and communicating with said fuel-feed compartment, said air feed passage following a course beneath the outer margin of the combustion chamber floor away from 90 said fuel-feed compartment and returning in the direction of said compartment beneath the interior portion of said floor and thereby subjecting the air to increasingly 95 hotter portions of the under face of said floor throughout its course through said passage to said fuel-feed compartment. 100

4. A furnace construction comprising a combustion chamber having a fuel-feed compartment at one end thereof, said combustion chamber having a continuous floor sloping gradually downward from the other end 105 of said chamber in the direction of said fuel-feed compartment, and provided with a drainage channel having an outlet for conducting any excess of fuel to the exterior of the furnace. 110

5. A furnace construction comprising a combustion chamber having a fuel-feed compartment at one end thereof, said combustion chamber having a continuous, unbroken floor sloping gradually in a direction longitudinal of the furnace and from one end of said chamber to the other, and also spanning the entire distance between the said fuel-feed compartment and the opposite end 115 of said combustion chamber. 120

6. A furnace construction comprising a combustion chamber having a fuel-feed compartment at one end thereof, the bottom of said chamber comprising flooring made up of a supporting structure of sheet metal and a layer of tiling carried by said supporting structure, said tiling being spaced apart at intervals to provide drainage passageways. 125

7. A furnace construction comprising a 130

combustion chamber having a fuel-feed compartment at one end thereof, the bottom of said chamber comprising flooring made up of sections of sheet metal connected together by interengaging marginal flanges forming a liquid-tight supporting structure, and a layer of tiling carried by said supporting

structure, said tiling being spaced apart by said marginal flanges to provide drainage passageways.

In witness whereof I hereunto affix my signature:

HARRY A. ATWATER,
